FISHING ROD HOLDER

Ivan H. Moore, Coffeyville, Kans.
(345 W. 6th St., Garnett, Kans. 66032)

Filed June 10, 1968, Ser. No. 12,283

Term of patent 14 years

Int. Cl. D22—08; D31

U.S. Cl. D22—22

FIG. 1 is a partial side elevational view of the fishing rod holder, the rod being shown in broken lines for illustrative purposes;

FIG. 2 is a front elevational view of the entire fishing rod holder embodying my new design;

FIG. 3 is a side elevational view of same; and

FIG. 4 is a top plan view of my holder as shown in FIG. 2.

I claim:

The ornamental design for a fishing rod holder, as shown and described.
